CABLE OPERATED CURTAIN
CONSTRUCTIONYale W. Ehret, Elkhart, Ind., assignor to The
Adlake Company, Chicago, Ill., a corporation
of Illinois

Application February 19, 1948, Serial No. 9,589

5 Claims. (Cl. 160—279)

1

This invention is concerned with improvements in cable curtain fixtures.

It is an object of the invention to provide an improved roller curtain installation particularly adapted for use in a railway passenger car or an automobile bus wherein the curtain is mounted in a window frame having opposite side guide channels which receive the ends of an apron assembly secured on the bottom of the curtain and wherein the position of the bottom of the curtain is adjustably controlled by engagement of the apron with a pair of cables, each cable having one end secured to the window frame adjacent the top of one side guide channel and the other end secured to the frame adjacent the bottom of the opposite side guide channel and each cable extending from its upper end downwardly along the adjacent side guide channel then through a longitudinal recess provided in the apron and down along the opposite side guide channel to the other end.

More particularly, it is an object of the invention to provide in a curtain installation of the type described an improved curtain apron assembly which is streamlined, which does not require endwise threading of the cables, and which is provided at its ends with cable guiding end members having a pile fabric on the outer surface thereof for engagement with the side guide channels.

It is a further object of the invention to provide in a curtain installation of the type described a curtain apron assembly which is readily and economically manufactured from extruded metal sections, which is adapted to be quickly assembled for initial installation and disassembled for subsequent repair or replacement of parts and which is provided with improved bearing surfaces for engagement with the cables at the ends to reduce wear on the cables and provide smooth operation.

These and other objects of the invention will be apparent from a description of the form of curtain installation which is illustrated, by way of example, in the accompanying drawing, wherein:

Fig. 1 is an elevation of a curtain installation which incorporates therein the principles of the invention;

Fig. 2 is a section on an enlarged scale, taken on the line 2—2 of Fig. 1;

Fig. 3 is a section on an enlarged scale, taken on the line 3—3 of Fig. 1; and

Fig. 4 is a detail of one end of the apron assembly with portions broken away, and

Fig. 5 is an exploded perspective view of one

2

end of the apron assembly with portions broken away.

The form of the curtain installation which is shown in the drawings comprises a curtain 10 installed in a window frame 11 which is secured in an aperture in the wall of a vehicle such as an automobile bus. The window frame 11 comprises a bottom sill 13, a top header 14 and side frame members 15 which include oppositely disposed guide channels 16. The window frame 11 supports a conventional sash unit (not shown) on its outer side. The curtain 10 is arranged to be raised and lowered adjacent the inner side of the sash.

15 The curtain 10 is attached to a roller 17 which is mounted on conventional brackets (not shown) arranged in the ends of the header 14. The bottom end 18 of the curtain 10 supports a transversely arranged apron assembly 19 having its 20 ends projecting into the oppositely disposed channels 16 and receiving a pair of cables 20 and 21.

25 Each of the cables 20 and 21 is attached at its upper end to opposite side guide channels 16 and each cable extends downward along the adjacent side guide channel to the apron 19, then through the apron 19 and down along the opposite side guide channel, being attached at the bottom of the channel. With this arrangement the bottom 30 end 18 of the curtain 10 is adjusted in raised or lowered position by frictional engagement of the cables 20 to 21 with the curtain apron 19.

35 A top end anchor plate 22 is provided for each cable which consists of a plate portion 23 having an elongated aperture 24 for receiving a screw 25 to secure it in adjusted relation on the base 26 of the channel 16 and a cable attaching portion 27 having an outwardly opening vertical slot 28 in which the upper end of the cable is secured by clinching.

40 A bottom anchor plate 29 is provided for each cable which includes a laterally extending stop member 30 for limiting downward movement of the curtain apron assembly 19. The plate member 29 is secured to the channel base 26 by an attaching screw 31. The stop member 30 extends outwardly of the channel base 26 and into the path of movement of the end of the apron assembly. The member 30 is provided with an aperture 32 in which the end of the cable is secured by an enlarged head 33 or the like.

45 The curtain apron assembly 19 comprises complementary or mating outer and inner members 34 and 35, respectively, which are preferably 50 formed from extruded aluminum sections. The

55

member 34 which forms the outer portion of the assembly 19 includes a relatively wide plate-like web portion 36 provided on its bottom edge with a relatively small inwardly directed flange portion 37. The outer member 34 is provided along its top edge with a thickened section 38 having a curved recess or groove 39 extending axially of the member and spaced some distance from the top margin for receiving the end 18 of the curtain 10 in clamping engagement. Immediately below the recess 39 an inwardly projecting spacer rib 40 of substantial thickness extends axially of the member intermediate the ends thereof, being cut away at each end 41 to accommodate an end assembly 42.

The apron member 35 which forms the inner portion of the apron assembly 19 includes a relatively wide plate-like web portion 43 provided at its bottom edge with an inwardly directed flange 44 which is complementary to and abuts with the flange 37 on the member 34 when the members are in assembled relation. The apron member 35 is provided along its top margin with a thickened section 45 and a longitudinally extending curved recess 46, the latter cooperating with the recess 39 in the member 34 to receive the end of the curtain 18.

The end assembly 42 comprises a base plate 47 having an inturned flange 48 along its lateral edge and a pair of semi-circular bearing members 49 to 50 which are positioned on the inner surface of the plate 47. The curved surfaces of bearing members 49 and 50 are in opposed relation and provide bearing surfaces for the cables 20 and 21, respectively. The base plate and bearing members 49 and 50 may be integrally formed or secured together by rivets 51 which may also secure the base plate 47 in proper position on the inner face of the web portion 36 of the apron member 34. The end fixture 42 extends beyond the end of the apron 19 and projects into the channel 16, the inturned flange 48 being spaced a sufficient distance from the bearing blocks 49 and 50 to accommodate the cables 20 and 21. The bearing blocks 49 to 50 are preferably provided with side flanges 52, 53, respectively, which extend over the curved bearing edges of the blocks and provide bearing grooves or channels for the cables 20 to 21.

A vertically extending bumper member 54 of rubber or similar resilient material is attached to the flange 48 with its ends extending above and below the top and bottom edges of the base plate 47. A U-shaped channel 55 of relatively thin material which is covered with a pile fabric 56 is secured in encompassing relation over the laterally projecting portion of the end assembly 42 with the pile fabric extending into engagement with the surfaces of the opposed walls of the channel 16. The members 54 and 55 may be conveniently secured to the flange 48 by screws 57.

The apron members 34 and 35 are preferably secured in assembled relation by means of screws 58 spaced along the length thereof which extend through holes provided in the web portion 43 of member 35 and engage in threaded engagement in mating holes provided in the rib formation 40 of member 34. The ends of the apron members 34 and 35 are preferably further connected by screws 59 extending through holes in the member 35 and engaging in threaded relation in holes 60 provided in the end assembly members 42.

While the invention has been illustrated as ap-

plied to railway car and bus installations, it will be understood that it is not limited to such installations. It may be employed wherever a retractable curtain is used and it is desirable to be able to readily raise and lower the bottom of the curtain. The details of construction and the materials referred to are intended as examples only. Other details of construction and other materials may be resorted to within the spirit of the invention.

I claim:

1. In a fixture adapted for attachment to the movable end of a cable operated curtain, complementary plate members secured together in spaced relation, said plate members having longitudinal rib formations which define a passageway between said plates for receiving therethrough the cables for said curtain, and metal guide members for said cables, secured at one end to said plate members, said rib formations being cut away at their ends to receive said guide members, said guide members having curved bearing surfaces engaged by said cables as they emerge from said passageway, said guide members having the ends thereof extending outwardly of said curved bearing surfaces and a pile fabric covering the outwardly extending ends of said guide members.

2. In a cable operated curtain fixture adapted for attachment to the movable end of the curtain, complementary members having inwardly directed longitudinally extending means defining a plurality of longitudinally directed recesses in said fixture when said members are in assembled relation, elongated means in one of said recesses engaging in clamping relation the end of the curtain and another one of said recesses receiving the operating cables for said curtain therethrough, and cable guide member having projecting end portions secured in the ends of said complementary members, each of said guide members having a channel-shaped pile fabric covered element removably positioned over the projecting end portion thereof.

3. In a cable operated curtain construction, said curtain being mounted in a window frame having side guide channels, a bead formation on the movable end of the curtain, a fixture comprising complementary front and back members having inwardly directed rib-like members providing a plurality of passageways between said front and back members when they are in assembled relation, the uppermost one of said passageways receiving said bead formation to clamp said fixture to said curtain, another one of said passageways receiving the operating cables for said curtain therethrough, and end guide members projecting laterally from the ends of said passageway for engagement by said cables as they emerge from said last mentioned passageway, said cables passing in opposite vertical directions from said guide members, each of said guide members having a pile-fabric covered outer portion for positioning the fixture in sliding relation in the side guide channels of the frame.

4. In a fixture attachable to the movable end of a cable operated curtain, complementary members having inwardly directed longitudinally extending members defining a plurality of longitudinally directed recesses in said fixture when said complementary members are in assembled relation, the uppermost one of said recesses receiving in clamping relation the end of the curtain and another one of said recesses receiving the operating cables for said curtain there-

through, and cable guide members secured at the ends of said cable receiving recess, each of said guide members comprising a plate-like base member provided with opposed upper and lower bearing surfaces for the cables and a projecting edge provided with an inturned flange spaced outwardly of said bearing surfaces, a pile fabric covered channel member encompassing the projecting portion of said base member and a bumper block having its ends extending above and below said base member, said channel member and said bumper block being secured to said inturned flange.

5. In a fixture adapted for connection to the movable end of a cable operated curtain, said curtain being mounted in a window frame having side guide channels, elongate complementary plate-like members having spacer means providing a passageway between said members when they are in assembled relation, said passageway receiving the operating cables for said curtain therethrough, and end guide assemblies having portions forming curved cable bearing surfaces, said guide assemblies being positioned adjacent
